JOHN HAYS HAMMOND, JR., OF GLOUCESTER, MASSACHUSETTS.

HARMONIC ORGAN.

Application filed July 19, 1924, Serial No. 726,908. Renewed June 5, 1928.

This invention relates to musical instruments and more particularly to organs arranged to emit the upper partials or harmonics of the notes of music.

5 I have found that by controlling the intensity of the harmonics of a note or notes the music takes on the quality of life and is rendered far more agreeable to the ear.

10 It is the main object of the present invention to provide an organ of improved construction, in which the harmonics of the several notes of the music may be controlled.

15 According to this object I provide means for varying the intensity of each fundamental note and separate means for varying the intensity of one or more harmonics of the note.

20 Another object relates to the provision of means for selecting one or more harmonics, the intensities of which are to be varied. By suitably selecting certain harmonics to be emphasized the timbre of the sound can be varied in very agreeable and pleasing combinations.

25 Other objects will appear from the following description taken in connection with the accompanying drawings in which

30 Figure 1 is a diagrammatic view of so much of an organ chamber as is necessary to an understanding of the invention;

Figure 2 is a diagrammatic view of a tablet and pedal control of the organ chamber of Figure 1; and

35 Figure 3 is a diagrammatic view of an automatic control of the organ chamber of Figure 1.

Figure 4 shows details of the pneumatic relay of Figure 3;

40 Figure 5 shows a side view of the swell motor removed.

Figure 6 is a section taken on the line 6—6 of Fig. 5; and Figure 7 shows details of a portion of the mechanism of Figure 2.

45 Referring to the drawings and more particularly to the form of the invention shown in Figures 1 and 2 there is shown an organ chamber 10 in which there is disposed a primary organ 11 and a plurality of secondary organ chambers such as 12, 13, 14 and 15 each containing a secondary organ of which only a secondary organ 17 within the organ chamber 12 and a secondary organ 18 within the organ chamber 13 are shown, it being understood that each of the organ 50 chambers includes a similar secondary organ.

The pipes of each of the secondary organs are tuned to the harmonics of the corresponding pipes of the primary organ 11 and are controlled by means of a convenient key board or manual 19. Thus when a single 60 key or the key board 19 is depressed a pipe in the primary organ and each of the secondary organs is sounded, and thus there is emitted from the primary organ a fundamental note corresponding in pitch to the 65 desired pitch as determined by the key depressed. Each of the primary organs may be of any conventional type of pipe organ but are preferably of the type which produces true fundamental tones, that is, with 70 few overtones or harmonics, such for example as the tibia family of pipes. For varying the intensity of sound of the fundamental notes of music the organ chamber 10 is provided with a plurality of shutters 25 75 which are pivotally mounted in a wall of the chamber 10 so that they may be rotated about their longitudinal axes. Each shutter is provided with a connecting rod 26 which is pivotally connected to an actuating arm 27, 80 one end of which is connected to a swell shutter motor 28 of conventional design and positioned within a casing 29. The connections of the swell shutter motor are brought out to terminals 30, 31, 32, 33 and 34 in well 85 known manner.

For varying the intensity of the sound emitted from each of the secondary organs there is provided a corresponding plurality of swell shutters 51, 52, 53 and 54 similar in 90 construction to the swell shutters 25 and each associated with one of the secondary organs. For operating the swell shutters there is provided a corresponding plurality of swell shutter motors 55, 56, 57 and 58 of 95 conventional design.

For controlling the swell shutter motors there is provided a pedal mechanism comprising a pedal 60 conventionally positioned so as to be readily actuated by the foot of the operator. The pedal 60 is pivotally mounted to be rotatable in a vertical plane and by means of a connecting link 61 is operatively connected with a slid able member 62 supported in a stationary frame member 63 forming part of the frame of the console. The sliding member 62 is formed of material which is a non-conductor of electricity and secured thereto is a strip of electrically conducting material 64 having 110

spaced contact portions 65, 66, 67, 68, 69, etc., corresponding in number to the total number of organs normally controlled from the single key board 19. A lead-in contact strip 70 supported upon an insulated arm 71 makes electrical contact with the conducting strip 64 in all positions of the pedal 60, and is connected to a source of energy such as a storage battery 72 for operating the swell shutter motors.

For interconnecting the contact segments 65 of the pedal 60 with the swell shutter motor terminals 30, 34 of the swell shutter motor 28, there is provided a plurality of contacts arranged in the path of the conducting segment 65 and connected by way of conductors 80, 81, 82 and 83 respectively, to the swell shutter motor terminals. The arrangement is such that upon a predetermined degree of movement of the pedal 60 the segments 65 makes electrical contact with its respective contacts successively and thus the operation of the swell shutter motor 28 and the actuation of the swell shutter 25 may be controlled in the usual step by step manner. A conductor 84 provides a return path from the swell shutter motor 28 to the pole of the battery 72 opposite to that to which the brush 70 is connected. Similarly, a row of contacts is provided with which the segment 66 makes contact upon a predetermined degree of movement of the pedal 60 and each of the said contacts is connected to conductors 85, 86, and 87 the purpose of which will be subsequently set forth. The contacting segment 67 is arranged to contact upon predetermined movement of the pedal 60 with contacts connected to the shutters 88, 89, and 90; the contact segment 68 with contacts connected to conductors 91, 92, 93; and the contact segment 69 with the contacts connected to the conductors 94, 95, 96 respectively. The several groups of contacts are disposed with relation to the associated contact segment so that a different degree of movement is required on the part of the pedal 60 to engage the several contacts, and thus different effects may be produced when the organ is played.

For selecting the effect which is to be produced there is provided a tablet rail comprising a plurality of tablets, such as tablets 100, 101, 102, 103, pivotally mounted upon a fixed supporting rod 104. Each of these tablets comprises a strip of ivory or celluloid mounted upon a metallic reinforcing back forming a contact member electrically connected to the rod 104. When the upper ends of these tablets are depressed, the metal portions forming the contact members engage respectively stationary contacts 105, 106, 107, 108. The contact 105 of the tablet 100 is electrically connected by means of a conductor 110 to one terminal

of the winding of a relay 111; the contact 106 by means of a conductor 112 to one terminal of the winding of the relay 113; the contact 107 by means of conductor 114 to one terminal of the winding of the relay 70 115, and the contact 108 by means of a conductor 116 to one terminal of the winding of the relay 117. The relays 111, 113, 115, and 117 are alike in construction and a description of one will suffice for all. 75

Each of said relays may consist of a rotatable member 120 supported in fixed brackets 121, 122. The shaft of the rotatable member 120 is provided with an armature 123 which is arranged to be controlled by the energization of the winding of the relay hereinbefore referred to, the armature being held in normal position as shown by means of a retractile spring 125. It is understood, however, that any suitable form of relay may be employed. The other terminals of the windings of the relays 111, 113, 115 and 117 may be connected together by means of a common conductor 126 to one pole of a source of energy, such as a battery 72. The other pole of the battery 72 is connected to the rod 104 forming a common terminal of the tablets 100, 101, 102 and 103. Each of said tablets is arranged so as to be maintained in either of two positions, that shown being the normal position in which contact is not made and the fully depressed position being one in which contact is made. 90

The relays 111, 113 are provided with contacts connected to a series of conductors 130, 131, 132. In the relay 113 electrical contact is made to these conductors 130, 131, 132 respectively by three moving contact members of the relay when the relay is energized. The moving members are connected to the conductors 87, 86, 85 respectively, thus when the relay 113 is energized the circuit is extended from contact segment 66 through to swell shutter motor 55 of the swell shutter 51. In the relay 111 electrical contact is made to these conductors 130, 131, 132 respectively by three moving contact members of the relay when the relay is energized, and the moving members are connected to conductors 90, 89, 88, respectively. Thus when the relay 111 is energized the circuit is extended from the contact segment 67 through to the swell shutter motor 55 of the swell shutter 51. 110

Similarly, the relays 115, 117 are provided with contacts connected to a series of conductors 133, 134, 135. In the relay 117 electrical contact is made to these conductors 133, 134, 135 respectively, by three moving contact members of the relay when the relay is energized. The moving members are connected to conductors 96, 95, 94 respectively. Thus when the relay 117 is energized, a circuit is extended from the contact segment 69 through to the swell shutter motor 56 of the swell shutter 52. In the relay 115 electrical 125

- contact is made to these conductors 133, 134, 135 respectively by three moving contact members of the relay when the relay is energized. The moving members are connected to conductors 93, 92, 91 respectively. Thus when the relay 115 is energized a circuit is extended through from the contact segment 68 to the swell shutter motor 56 of the swell shutter 52.
- 10 The swell shutter motor shown in Figures 5 and 6 consists of a box 210 in which is mounted a bellows 211 consisting of four sections each mounted on a base 212, 213, 214 and 215, the last named being secured to the top of the box 210. The box 210 is connected to any suitable source of air pressure by means of a pipe 216. Secured to the base 213 is a second small bellows 219 composed of two sections, and secured to the base 214 is a third small bellows 220 composed of one section. The large bellows 211 is secured to one end of a rod 223, the other end of which is connected to the swell shutters of the organ. The interior of bellows 218 is connected by a passage way 225 cut in the base 212 to the interior of the section mounted on the base 212. The bellows 218 is so constructed that air can easily pass through from one end to the other by means of openings 226 and 227 provided in the bases 213 and 214. The base 215 is provided with an opening 228 which extends through the box 210 and into a chamber 229 provided in the side of the primary mechanism box 230 which is mounted on the top of box 210.
- It is evident, therefore, that the chamber 229 is always in communication with the bellows mounted on the base 212. In a similar manner the interiors of the bellows which are mounted on the bases 213, 214, and 215 respectively, are constantly in communication with chambers 231, 232 and 233 respectively, which are indicated by dotted lines in Fig. 5. Each of these chambers is provided with two holes 234 and 334. In the chambers 229, 231, 232 and 233 are mounted valves 235 carried on rods 236, which are held in alignment at one end by means of brackets 237 and are connected at their other ends to diaphragms 238 which are secured to the wall of a longitudinal chamber 238 provided in the primary mechanism box 230. Back of each diaphragm 238 is a chamber 240 which is connected by a passage way 242 to the interior of a chest 243. A bleeder hole 242 is provided which connects chamber 239 with the passage 242. Chamber 239 is connected to the interior of the box 210 by a passage 334, shown in Fig. 6.
- For controlling the chest 243 there is provided a casing 244 which carries an electro magnet 245 provided with a winding 246, the two ends of which are connected to wires 247 and 248. In the inside of the casing 244 is an armature 250 held in place over the electro magnet 245 by means of pins 251. When the magnet is energized the armature 250 closes a hole 252 provided in the casing 244.
- The wire 247 of the chest magnet controlling the chamber 229 is connected to a wire 256. The wire 247 of the chest magnet controlling the chamber 231 is connected to a wire 257. The wire 247 of the chest controlling the chamber 232 is connected to a wire 258 and the wire 247 of the chest magnet controlling the chamber 233 is connected to a wire 259. The wires 248 of the four chest magnets are connected to a common wire 260.
- In the operation of the swell motor shown in Figs. 5 and 6 when the wire 256 is energized an electric current passes through the winding of the chest magnet 245 causing the armature 250 to be pulled away from the opening 252. This allows air to escape from the chamber 240 and the pressure of the air in the chamber 239 forces the diaphragm 238 to the left, thus pulling the valve 235 to the left and closing the hole 334, and opening the hole 234, thus connecting the interior of the bellows mounted on the base 212 to the atmosphere. The pressure of the air in the box 210 will therefore cause this bellows to be collapsed, thus pulling the rod 223 up an amount corresponding to the amount the bellows is collapsed. When the wire 257 is energized a similar action takes place in the bellows on the base 213, which is likewise collapsed, thus moving the rod 223 up an additional amount. A similar procedure takes place as each wire 258 and 259 is energized until the entire bellows is fully collapsed, thus pulling the rod 223 up the maximum amount. As the wires 259, 258, 257 and 256 are successively de-energized, the magnets 245 will be de-energized and the armature 250 will be moved up against the holes 252 by the air entering the passage 242 through the bleeder hole 242. At the same time this air acting against the left hand side of the diaphragm 238 causes the valve 235 to be moved to the right; thus closing the hole 234 and opening the hole 334, thus allowing air to enter each section of the bellows which will then be expanded due to the pull on the rods 223 until the bellows is expanded to its full amount as shown in Fig. 6.
- In the operation of this form of the invention when it is desired to produce a certain tonal effect the tablets 100, 102 for example, may be depressed at their upper ends to close the circuit of the windings of the relays 111, 115. A portion of the relay 111 connects the conductors 88, 89, 90 to conductors 132, 131, 130 respectively. A portion of the relay 115 connects the conductors 91, 92, 93 to conductors 135, 134, 133 respectively. It will now be seen that when

the organ is played and the pedal is operated the segment 65 of the pedal is effective for controlling the swell shutter motor 28 and thus controlling the intensity of sound emitted from the primary organ 11; and also that the segment 67 is effective for controlling the swell shutter motor 55 for varying the intensity of sound emitted from the secondary organ 12; and that the segment 68 is effective for controlling the swell shutter motor 56 for varying the intensity of the sound emitted from the secondary organ 13. In its normal operation the pedal 60 is very carefully adjusted by the foot of the operator and it will be seen that the intensity of sound emitted by the secondary organs, and thus the intensity of the harmonic notes, is controlled in a certain predetermined manner. Furthermore, by suitably selecting a tablet only desired harmonics will be emphasized and variations in intensity of these selected harmonics can be made independently. Restoration of the pedal to normal will of course restore the swell shutters and decrease the volume of sound, and the operation may be repeated as many times as may be desired. The relation between the opening of the various shutters is determined by the relative location of the contact segments 67, 68, etc. with respect to their associated group of contacts.

When it is desired to produce a different harmonic effect the tablets 100, 102, may be returned to their initial positions and another combination of tablets, such as 101, 103 may be depressed. In this instance the relays 113, 117 will be operated, the relay 113 connecting the conductors 85, 86, 87 to conductors 132, 131, 130, respectively, and the relay 117 connecting the conductors 94, 95, 96 to conductors 135, 134, 133 respectively. Thus a circuit is extended from the contact segment 66 to swell shutter motor 55 of the swell shutter 51, and from the contact segment 69 to the swell shutter motor 56 of the swell shutter 52. The contact segments 66 and 69 are positioned in different relation to the respective groups of contacts and thus different effects dependent upon such relationships are produced.

In the modified form shown collectively in Figs. 1 and 3 automatic means is provided for controlling the notes to be played. This comprises a music roll mechanism 140, a swell shutter control mechanism 141, and a set of pneumatic relays 142 which are operated by the mechanism 141 and which in turn control the swell shutters of the organ.

The music roll mechanism consists of a tracker bar 145 mounted in the casing 146, two rolls 147 and 148, and a strip of perforated paper 149, which is unwound from the roll 147 and wound upon the roll 148 and passes over the tracker bar 145. Any suitable standard mechanism may be used for

producing this motion which need not be more fully described herein. The perforations in this paper when they come opposite the holes in the tracker bar cause the notes to be sounded on the organ, by any well known and suitable means. Thus, when a note is sounded on the organ 11, Fig. 1, the corresponding notes on the harmonic organs 17 and 18 will also be sounded.

The swell shutter control mechanism 141 comprises two rolls 151 and 152, the tracker bar 153. Wound upon the two rolls 151 and 152 and passing over the tracker bar 153 is another sheet of perforated paper 154. This paper is caused to move from one roll to the other by any suitable means, so arranged that the two sheets of paper 149 and 154 will move in synchronism.

The paper strip 149 is provided with a plurality of holes which when they pass in front of the tracker bar 145 cause corresponding notes in the organs 11, 17 and 18 to be sounded as previously described. The paper strip 154 is provided with suitable longitudinal slits of varying lengths which co-operate with holes 160 provided in the tracker bar 153. The holes 160 are connected by a plurality of pipes 161 to the primaries of a corresponding number of bellows 162 mounted upon a wind duct 163. The wind duct 163 is connected by a pipe 164 to a suitable source of suction not shown for operating the bellows 162. Each bellows is provided with an arm 165 which when the bellows is collapsed presses a contact 166 against a strip of conducting material 167. The contacts 166 are connected to the conductors which operate the swell shutter motors shown in Fig. 1, and the strip 167 is connected by a conductor 168 to one side of a battery 169, the other side of which is connected by the common return conductor 129 from the swell motors as previously described.

In the operation of the modified form of the invention shown in Figs. 1 and 3, the paper strip 149 when it passes over the tracker bar 145 plays the music on the organ in a well-known manner.

The paper strip 154 when it passes over the tracker bar 153 causes certain groups of openings to pass in front of the holes 160 in the tracker bar, thus allowing air to enter the corresponding primaries and operate the required bellows 162, thus causing the corresponding contact 166 to engage the strip 167, thus closing the circuit to the swell motor shown in Fig. 1. By the proper cutting of the holes in the paper strip 154 any number of circuits may be chosen to any one of the swell motors, thus opening the shutters operated by these motors a predetermined amount. In this way any desired combination of shutter opening may be obtained and this can be varied at will by

the proper selection of holes in the paper 154 so as to produce the desired musical effect by the combination of the notes of the harmonic organs 17 and 18 with the corresponding notes of the primary organ 11.

It may be found desirable to run the paper strip 154 at a much higher speed than the strip 149 so as to produce the rapid changes in effect by the operation of the swell 10 shutters that would be necessary to give the desired tonal effects. The ratio of speeds between the paper strips 149 and 154 must be kept constant so that the proper tonal effects occur at the time that the corresponding 15 notes in the paper strip 149 register with the holes in the tracker bar 140.

It will be readily understood that in either of the embodiments shown only one of the harmonic organs may be selectively actuated 20 when desired. Another embodiment comprises Figs. 1 and 2 when a single organ may be employed by depressing only a single tablet and in the embodiment shown in Figs. 1 and 3 a single organ may be employed by 25 properly cutting the paper strip 154. Thus it will be seen that the intensity of sound emitted from a harmonic organ will be varied as may be desired.

The inventive thought which this application is based upon is broader than the specific embodiment herein described. The scope of the invention is therefore not to be limited thereby, reference being had to the appended claims for that purpose.

35 What I claim is:—

1. The combination of a primary organ, a plurality of secondary organs each of which are adapted to play notes which are harmonics of a note of the primary organ respectively, a key board for simultaneously actuating said organs, with means for controlling the intensity of sound emitted from one of the secondary organs and a selective device for predetermining the secondary 45 organ to be controlled.

2. A musical instrument comprising an operating mechanism, wind sounding means controlled thereby for producing a plurality of sounds spaced apart by octaves and means for causing the loudness of certain of said sounds produced to vary from a predetermined degree without changing the loudness of the remaining sounds.

3. A musical instrument comprising an operating mechanism, and wind sounding means for causing the timber to vary by variations in the upper partials of the sounds produced.

4. In a musical instrument, wind sounding means for producing a plurality of substantially simple harmonic motions in the air comprising a fundamental and a plurality of harmonics, means for controlling said harmonic motions so as to produce a composite note, means for varying at will

the intensity of any of the partials of said composite note relative to the other partials and means for varying the intensity of said composite note.

5. A musical instrument comprising an operating mechanism, wind sounding means controlled thereby for producing a plurality of composite tones each comprising a fundamental and a plurality of harmonics, means for varying the intensity of any one of the partials of said composite tones relative to the other partials, and means for varying the intensity of the entire composite tones.

6. A wind musical instrument comprising a key, wind sounding means controlled by said key for producing a composite tone including a fundamental and a plurality of harmonics, means for varying independently of said key the intensity of any of the partials of said composite note relative to the other partials, and means for varying the intensity of said composite note as a whole.

7. A wind musical instrument comprising an organ chamber, a primary organ within said organ chamber, a plurality of secondary organ chambers within said organ chamber, a secondary organ within each of said secondary organ chambers the pipes of each of said secondary organs being tuned to the harmonics of the pipes of the primary organ respectively, a keyboard for controlling said pipes to produce music and arranged so that each of the keys of said keyboard controls a pipe of the primary organ, and a pipe in each of the secondary organs to produce a composite tone comprising a fundamental and a plurality of harmonics, a plurality of shutters for effectively controlling the intensity of sound emitted from the first named organ chamber, a swell motor for controlling said shutters, a plurality of shutters for each of said secondary organ chambers for effectively controlling the intensity of sound emitted from the respective secondary organ, a swell shutter motor for controlling the shutters of each secondary organ chamber respectively, means for selectively controlling the secondary organ chamber shutter motors, and means for controlling the swell motor of said first named organ chamber.

8. A wind musical instrument comprising an organ chamber, a primary organ within said organ chamber, a plurality of secondary organ chambers within said organ chamber, a secondary organ within each of said secondary organ chambers, the pipes of each of said secondary organs being tuned to the harmonics of the pipes of the primary organ respectively, means for controlling said pipes selectively to produce music and arrange to actuate simultaneously a pipe of the primary organ and a pipe in each of the secondary organs to produce a composite tone comprising a fundamental and a plural-

ity of harmonics, a plurality of shutters for effectively controlling the intensity of sound emitted from the first named organ chamber, a swell motor for controlling said shutters, a plurality of shutters for each of said secondary organ chambers for effectively controlling the intensity of sound emitted from the respective secondary organ, a swell shutter motor for controlling the shutters of each secondary organ chamber respectively, means for selectively controlling the secondary organ chamber shutter motors independently of said pipe controlling means, and means for controlling the swell motor of said first named organ chamber.

9. A wind musical instrument comprising an operating mechanism, organ pipes controlled thereby for producing a plurality of composite tones each comprising a fundamental and a plurality of harmonics, means for varying the intensity of any one of the partials of said composite tones relative to the other partials, and means for varying the intensity of the entire composite tones.

10. A wind musical instrument comprising a key, a plurality of organ pipes controlled by said key for producing a composite tone including a fundamental and a plurality of harmonics, means for varying independently of said key the intensity of any of the partials of said composite note, relative to the other partials, and means for varying the intensity of said composite note as a whole.

11. A wind musical instrument comprising

ing a control device, a plurality of organ pipes controlled by said device for producing a composite tone including a fundamental and a plurality of harmonics, means for varying independently of said device the intensity of any of the partials of said composite note, relative to the other partials, and means for varying the intensity of said composite note as a whole.

12. A wind musical instrument comprising a key, an organ pipe controlled by said key for producing a fundamental note, a plurality of organ pipes controlled by said key for producing harmonic notes of the fundamental, means for varying independent of said key the intensity of sound produced by any of said pipes relative to the sounds produced by the other pipes, and means for varying the intensity of the composite note produced by all of said pipes.

13. A wind musical instrument comprising a control device, an organ pipe controlled by said device for producing a fundamental note, a plurality of organ pipes controlled by said device for producing harmonic notes of the fundamental, means for varying independent of said device the intensity of sound produced by any of said pipes relative to the sounds produced by the other pipes, and means for varying the intensity of the composite note produced by all of said pipes.

In testimony whereof I hereunto affix my signature.

JOHN HAYS HAMMOND, JR.
